UNITED STATES PATENT OFFICE.

ALFRED GAULARD, OF PARIS, FRANCE, ASSIGNOR TO ATELIERS DES VOSGES, OF PARIS, FRANCE, A CORPORATION OF FRANCE.

AUTOMATIC BRAKE FOR WEAVING LOOMS.

Application filed May 22, 1926, Serial No. 110,851, and in France May 29, 1925.

The present invention relates to an automatic brake for weaving looms obviating all attention of the weaver when the loom is started or stopped, or when the machine is inoperative and the loom is to be operated by hand, for unweaving or like purposes.

For this purpose the brake, the object of the invention, is essentially characterized in that when the loom is stopped by the unclutching lever, it will act automatically and in a momentary manner, this being followed by an automatic release of the brake, and the brake will remain in this latter position during the entire stopping period of the machine, even should the loom be moved by hand, and also when the machine is restarted.

To effect this automatic application of the brake which is immediately followed by an automatic release of the said brake, I utilize the displacement of the unclutching lever which is actuated, to stop the machine, either by hand or by any one of the supplemental mechanisms such as the weft stop motion, the warp stop-motion, the automatic continuous weft feeding device or the like.

The following description with reference to the appended drawings which are given by way of example, relates to a form of construction of my said automatic brake.

Fig. 1 is a side elevation of the apparatus, and Fig. 2 is the corresponding front elevation.

1 is the brake wheel or drum, coacting with the leather faced brake shoe, 2, below which is disposed, to assure the progressive action of the brake, an india rubber buffer which is slidable in the main body of the brake shoe; the said shoe is pivoted at 3 and is controlled, through suitable gear such as the rod 4; the bell crank 5 and the rod 6, by the controlling lever 7 to which the rod is attached at 8.

The lever 7, which is actuated by the releasing device when it is disposed for uncoupling purposes in order to effect the momentary automatic braking and the automatic brake release which immediately succeeds the braking, is pivoted to a stationary axle 9 mounted on the machine frame and is constantly urged by the spring 10 which applies it by its heel 11 against a stop 12, the said action being momentarily counter-

acted during the braking, the lever 7 being then raised by the displacement of the expansion device and applying the brake by means of the rods 4 and 6 and the bell crank 5, or like transmission gear. 60

The ascent of the lever 7—contrary to the action of the spring 10,—for braking purposes, is effected by the cam portion 13 formed on its lower edge, which is raised for a certain time depending upon the movement 65 of the releasing device for disengaging the brake, by means of an element secured to the said releasing device and herein consisting of a lever 14 which is pivoted at 15 to the unclutching lever 16 and has at the lower 70 end the heel 17, said lever 14 being held stationary and raising by its upper end 18 the controlling lever 7 during the displacement of the releasing device for disengaging the 75 brake, but yielding, during the movement of the releasing device in the other direction, to the starting device.

The operation of the automatic brake is as follows:

During the functioning of the loom, the 80 unclutching lever 16, having been moved at the start in the direction of the arrow *a* and assuming the position shown in the dot and dash lines at 16', will be displaced when actuated by hand or by a suitable brake releasing device, in the direction contrary to the arrow *a*, thus stopping the machine. During this displacement of the releasing lever, the lever 14 which is mounted thereon, will tend, when its upper end 18 makes 85 contact with the cam 13, to pivot in the contrary direction to the arrow *b*, but since it bears by its heel 17 against the releasing device 16, the pivoting movement will be prevented, so that it will remain stationary, 90 and this will cause by the action of its upper end 18 upon the cam 13 the ascent of the controlling lever 7 against the antagonistic action of the spring 10, so that the shoe 2 will be applied against the brake wheel 1, 95 100 affording a progressive braking by the action of the said shoe and the presence of the said india rubber buffer.

This braking action is only temporary, since it is followed by a release of the brake 105 shoe when the end 18 of the lever 15 has passed beyond the lowest point of the cam 13 of the controlling lever 7, which again descends under the action of the spring 10, thus releasing the brake shoe; the brake re- 110

lease being terminated when the release device attains its extreme position (shown in the full lines at 16) and the end 18 of the lever 14 leaves the cam 13 of the lever 7 which is applied by its heel 11 against the stop 12 and which through the rods 4 and 6 and the bell crank 5 disengages the brake shoe 2 to such a degree that there will be no more friction.

On the contrary, when the machine is in the inoperative position and the said releasing device is moved in the direction of the arrow *a* for braking purposes, the lever 14 will yield when its upper end 18 makes contact with the cam 13 and will swing in the direction of the arrow *b* so that it will not modify the position of the lever 7; the lever 14 will be brought back, after clearing the cam 13, by the weight of its heel 17 whose motion is limited by its contact with the releasing lever 16.

Obviously the said automatic brake is susceptible of various modifications in detail without departing from the principle of the invention, and equivalent means or devices may be employed.

What I claim is:

1. An automatic brake for weaving looms, characterized in that the control of the brake shoe is realized through the medium of transmission gear such for instance as rods and a bell crank, by a control lever pivoted to a fixed point secured to the frame, actuated by the unclutching device, when it is displaced for disengaging the brake, to effect a momentary automatic braking followed by an automatic brake release which is immediately consecutive, said pivoted lever being subjected to the constant action of a spring which applies it by means of a heel against a stop, and thus in a permanent position in which it holds the brake in the released position, this constant action of the spring being momentarily counteracted during the braking, the control lever being then actuated by an element mounted on the releasing device.

2. The disposition upon the pivoted control lever controlling the brake shoe and subjected to the constant action of a spring as referred to in claim 1, in order to momentarily counteract the effect of the said spring to carry out the braking, of a cam or projection which is raised for a determined time by the element mounted on the releasing device during the displacement of the releasing device for uncoupling purposes.

3. The realization of the momentary lifting of the pivoted lever as referred to in claim 1 having a cam or projection, by means of an element mounted on the releasing device, consisting, in this event, of a lever mounted on the releasing device and whose upper end may make contact with the cam

of the control lever and whose lower end 65 comprises a heel, said lever, mounted on the releasing device, bearing against it by its heel during the motion of the releasing device when the uncoupling takes place, and raising the cam by its top end, and pivoting, on the contrary, during the motion of the releasing device in the other direction, for starting the machine.

4. An automatic brake for weaving looms, comprising a friction drum rotative with 75 the loom mechanism, a pivoted brake shoe cooperating therewith, a lever and pull rod system cooperating therewith, and having a cam member, a clutch, operative between the loom mechanism and a power source and 80 having an operating lever, a swinging auxiliary lever mounted thereon, a cam cooperating with said brake lever system and said swinging lever upon said clutch lever whereby movement of said clutch lever to release 85 the clutch, actuates said brake and whereby said swinging lever is relieved from said cam during the engaging motion of said clutch lever.

5. An automatic brake for weaving looms, 90 comprising a brake drum and a brake shoe having a leather face and an elastic rubber backing means.

6. An automatic brake for weaving looms, comprising a friction drum, a brake shoe co-operating therewith, a leather face thereon, and means comprising a rubber buffer positioned within a back recess in the body of 95 said brake shoe cooperating with said leather friction surface.

7. An automatic brake for weaving looms, comprising a friction drum rotative with the loom mechanism, a pivoted brake shoe co-operating therewith, having a leather braking surface and an elastic rubber backing 105 means cooperating therewith, a lever and pull rod system cooperating therewith, having a cam member, a clutch operative between the loom mechanism and a power source and having an operating lever, a swinging auxiliary lever mounted thereon, a cam 110 cooperating with said brake lever system and said swinging lever upon said clutch lever whereby movement of said clutch lever to release the clutch, actuates said brake and whereby said swinging lever is relieved from 115 said cam during the engaging motion of said clutch lever.

8. An automatic brake for weaving looms, comprising a friction drum, a brake shoe, a 120 cooperating pull rod and lever brake rigging, a cam lever member therein, and a weighted bell crank lever cooperating with said cam and attached to a loom actuating lever.

In testimony whereof I affix my signature.

ALFRED GAULARD.
